(57) **CLAIM**

The ornamental design for a cylinder head air guide, as shown and described herein.

DESCRIPTION

FIG. 1 is a left front perspective view of an engine cylinder head and air guide of the present invention.

FIG. 2 is a top plan view of the engine cylinder head and air guide of FIG. 1.

FIG. 3 is a left side view of the engine cylinder head and air guide of FIG. 1.

FIG. 4 is front view of the engine cylinder head and air guide of FIG. 1.

FIG. 5 is a rear view of the engine cylinder head and air guide of FIG. 1.

FIG. 6 is a right side view of the engine cylinder head and air guide of FIG. 1.

FIG. 7 is a bottom view of the engine cylinder head and air guide of FIG. 1.

FIG. 8 is an inside perspective view of the air guide removed from the cylinder head of FIG. 1.

FIG. 9 is an inside side view of the air guide of FIG. 8.

FIG. 10 is a top plan view of the air guide of FIG. 8.

FIG. 11 is a front view of the air guide of FIG. 8.

FIG. 12 is a rear view of the air guide of FIG. 8.

FIG. 13 is an outside side view of the air guide of FIG. 8; and, FIG. 14 is a bottom view of the air guide of FIG. 8.

The broken lines in the drawing views are included for the purpose of illustrating portions of the cylinder head air guide that form no part of the claimed design.
